Primary Examiner — Catherine Tuttle(74) Attorney, Agent, or Firm — Kenneth H. Ohriner;
Perkins Coie LLP(57) CLAIM

The ornamental design for a football kicking tee, as shown and described.

DESCRIPTION

FIG. 1 is a front, top and left side perspective view of the football kicking tee embodying my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an exploded perspective view thereof.

The tee is symmetrical about a front-back centerline.

The circumferential lines on the triangular flaps shown in FIGS. 1 and 6 are contour shading.

The dashed lines are included for the purpose of illustrating the portions of the football kicking tee that form no part of the claimed design.
